UNITED STATES PATENT OFFICE.

ADAM H. PRENZEL, OF HALIFAX, PENNSYLVANIA.

LASTING ATTACHMENT FOR STAPLING MACHINES.

Application filed July 9, 1925. Serial No. 42,543.

To all whom it may concern:

Be it known that I, ADAM H. PRENZEL, a citizen of the United States, and resident of Halifax, in the county of Dauphin and State of Pennsylvania, have invented certain new and useful Improvements in Lasting Attachments for Stapling Machines, of which the following is a specification.

This invention relates to improvements in stapling machines, and it consists of the constructions, combinations and arrangements herein described and claimed.

An object of the invention is to provide an attachment for stapling machines, so arranged that the upper is worked or drawn over the last immediately prior to the driving of a staple or other temporary fastening means, use being made of the power imparted to the rocker and staple guide in stapling operations, thereby combining the principal function of a lasting machine with that of the stapling machine.

Other objects and advantages appear in the following specifications, reference being had to the accompanying drawings, in which

Figure 1 is a side elevation of enough of a stapling machine to illustrate the embodiment of the lasting attachment.

Figure 2 is a side elevation of the lasting attachment as seen from the opposite side of the stapling machine.

Figure 3 is a sectional view of the stapling machine showing a sole flange in place upon the anvil and the upper in place upon the lasting fingers.

Figure 4 is a detail sectional view on the line 4—4 of Figure 3 showing how the upper is supported by the lasting fingers.

Figure 5 is a detail side elevation of the staple guide and anvil of the stapling machine, illustrating the relationship of the lasting fingers.

Figure 6 is a sectional view showing the staple guide moved down and illustrating the action wherein the upper is drawn tightly upon the last.

Figure 7 is a detail sectional view on the line 7—7 of Figure 6, showing how the divider coacts with the lasting fingers in making a tight fold in the upper.

Figure 8 is a detail plan view of the lasting fingers.

Figure 9 is a detail side elevation illustrating how an adjustment of the lasting fingers produces a more pronounced fold-tightening or drawing action of the divider.

This invention is an improvement on the stapling machine disclosed in my co-pending application filed August 21, 1922, Serial #583,322, and is designed with a view of being cooperatively used in connection with the machine for molding insole flanges described in my co-pending application for Letters Patent filed July 9, 1925, Serial Number 42,545 and handling the particular insole produced by said machine, said insole being described in my co-pending application for Letters Patent filed July 9, 1925, Serial No. 42,544. The stapling machine in my co-pending application Serial Number 583,322 has incorporated therein a pair of rigidly supported lasting fingers with which a fold controller on the staple guide cooperates for the purpose of producing folds in the upper preparatory to the driving of the staple. The improvement herein disclosed provides for a yieldable mounting of the lasting fingers and in addition to the fold controller there is provided a divider upon the rocker intended to coact directly with the lasting fingers to produce a tight fold and to stretch the upper tightly upon the last.

Briefly described, those parts of the stapling machine necessarily described and illustrated to convey an understanding of the lasting attachment comprise a connecting rod 2 which is capable of operation by a suitable treadle (not shown). The upper end of the connecting rod is pivotally joined at 3 to an actuating link 4 which, in turn, is pivoted at 5 to a dog 6 having a pivotal mounting at 7 to a portion of the frame 8. The frame is suitably mounted upon a standard (not shown).

A rocker arm, pivoted at 12 to the actuating link 4 depresses the rocker 14 through its pivotal connection 15 upon each operation of the connecting rod 2, and necessarily of the treadle to which it is joined at the bottom. The rocker is suitably pivoted upon the frame. The driving arm 17 is pivoted at 18 to a link 19 which in turn is pivoted at 20 to the frame. A depression of the treadle causes the depression of the rocker 14, and simultaneously therewith causes the disengagement of the dog 6 from the clutch 21 and the heel 22 from the recess 23 in the hub of an eccentric 24. As the shaft 25 revolves continuously while the machine is in operation, the disengagement of the clutch 21 causes the eccentric to be

locked to the shaft so that the eccentric arm 26 rocks the driving arm 17 on its pivot 18 and causes the driver 27 to insert a staple into the shoe leather which is in the proper place.

The engagement of the clutch 21 with the continuously rotating part from which the driving motion is derived is severed when one revolution is made and the dog is again reached. The above description, although brief, is sufficient to enable the reader to gain a general idea of the stapling machine, and attention is now directed to the lasting attachment which constitutes the invention. 15 The sole 28 of a shoe to be lasted is temporarily secured to a wooden last 29 (Figs. 3 and 6), an upper 30 (consisting of a lining and upper leather) being so applied to the last that the marginal portion extends 20 well out upon the channel flange 31. The channel flange is molded into the cross sectionally concaved shape shown so that it can readily be fitted upon the anvil 32 by any appropriate means, particularly by the 25 insole flange molding machine disclosed in one of the copending applications above referred to.

Staples are inserted through the upper 30 and flange 31 by the action of the driver 32. The staples provide temporary fastening means for the upper upon the channel flange. But in inserting the staples it is necessary to draw the upper 30 tightly upon the last 29 and in order that this may be 30 done substantially simultaneously with the driving operation provision is made of a pair of lasting fingers 33 and 34, a divider 35 and a fold controller 36.

Upon placing the flange 31 upon the anvil 32 the operator sees to it that the marginal portion of the upper 30 extends over the lasting fingers 33 and 34 as shown in Figures 3 and 4. The divider 35 passes down into the space between the lasting 40 fingers 33 and 34 stretching the upper 30 tightly (Fig. 7) forming folds or puckers upon the lasting fingers, thereby taking up all slack in the upper. The lasting fingers are now yieldably mounted, and the yielding 45 of the lasting fingers (compare full and dotted line positions in Fig. 6) occurs when the divider 35 passes down in the operation of driving a staple. The divider 35 and the lasting fingers in combination exercise a 50 gripping function upon the upper to draw the upper tightly over the last 29. This function is accentuated by the controller 36 which jams down upon the upper in front of the staple guide 37, insuring close contact of the upper with the channel flange 31.

A block 38 provides a support upon which the lasting fingers 33 and 34 are mounted for individual pivotal movement at 39. Springs 40 and 41, attached to the shanks 60 42 and 43 of the lasting fingers, pull the

shanks down upon a stop 44 to thereby maintain a normal relationship of the lasting fingers with the divider 35. But the stop 44 is adjustable at 45 so that the position of the lasting fingers in respect to the divider 70 can be altered (see Fig. 9) thereby causing a more pronounced stretching of the upper when the divider advances between the lasting fingers, presuming that the adjustment has been such as to bring the lasting fingers 75 closer to the divider.

A further adjustment of the lasting fingers 33 and 34 permits regulating the position thereof in respect to the anvil 32. This adjustment is made through the block 38 80 and comprises a slot 46 in the anvil support 47 (Fig. 2) through which slot one or more machine screws 48 pass into the block to hold the block in the desired position in the recess 49 provided in the support. 85

A slender rod 50 passes through the lasting fingers 33 and 34 (Figs. 5 and 8) and carries knurled nuts 51 on the threaded ends so that adjustment of the tension of springs 52 may be made. The springs provide for any necessary yielding of the lasting fingers, and inasmuch as the lasting fingers are mounted for independent pivotal motion the yielding function thereof becomes differential. One lasting finger may yield more than the other according to circumstances that may arise in the operation of the machine. 95

An adjustment is also provided for the fold controller 36. This element is composed of a metallic plate (Fig. 5) which is appropriately bent at the lower end to assume a proper relationship with the staple guide 37, the greater part of the plate being slotted at 53 to receive a pair of screws 100 54 which, upon being loosened, permit up and down movement of the fold controller so that the lower edge projects more or less beyond the extremity of the staple guide. The extent to which the fold controller 105 jams the upper 30 into the outer corner of the channel flange 31 depends upon the amount of adjustment of the controller beyond the staple guide. 110

The operation may be briefly reviewed 115 to advantage. The last 29 (Figs. 3 and 6) is composed of wood and has a channeled insole 28 temporarily tacked thereto. The upper 30 is applied on top of the last, the margin being ample to extend well beyond the channel flange 31. This channel flange is formed into the shape illustrated by a particular process, and the formation given the channel flange makes it easy to insert it upon the anvil 32 of the stapling machine. When thus applying the channel flange the operator sees to it that the margin of the upper 30 rests upon the pair of lasting fingers 33 and 34 as shown in Figures 3 and 4. 120

125

130

The machine is now operated to drive the staple, and when thus operated assumes the position in Figure 6. The rocker 14 moves down toward the anvil 32 and in doing so, the divider 35 presses that part of the upper which rests upon the lasting fingers down into the space between the lasting fingers (Fig. 7) thereby not only taking up some of the looseness in this part of the

upper but by virtue of the fact that the lasting fingers are yieldably mounted, causing the stretching of the upper downwardly over the toe of the last. The edges of the divider 35 grip the upper at the sides of the lasting fingers (Fig. 7) and in moving down cause a stretching of the upper as stated.

At the same time that this happens the fold controller 36 jams down upon the upper and assists the foregoing stretching action.

20 The various actions occur substantially simultaneously, the total effect being to stretch the upper tightly and at the same time form a fold in the marginal portion to take up all slack. The climax of one operation 25 occurs when the staple is driven through the upper and into the channel flange 31. The rocker 14 is permitted to raise, whereupon the shoe is moved a little farther and the foregoing operation is repeated. The 30 stapling operation on one shoe having been completed finds the slack in the upper taken up by a series of folds, the upper being drawn tightly down upon the last so that no puckers or looseness whatever appears.

35 While the construction and arrangement of the improved lasting attachment is that of a generally preferred form, obviously modifications and changes may be made without departing from the spirit of the 40 invention or the scope of the claims.

I claim:—

1. A lasting attachment for a stapling machine having a staple guide, said lasting attachment comprising spaced apart means upon which the margin of an upper is rested preparatory to stapling, means which move with the staple guide to press the marginal upper between and into gripping engagement with said spaced apart means, 45 and means permitting yielding of said spaced apart means in the direction of movement of the staple guide causing a pull on the upper over a last by which it is carried.

55 2. A lasting attachment for a stapling machine having a staple guide, said lasting attachment comprising spaced apart means upon which the margin of an upper is rested preparatory to stapling, means which move with the staple guide to press the marginal upper between and into gripping engagement with said spaced apart means, means permitting yielding of said spaced apart means in the direction of movement of 60 the staple guide causing a pull on the upper

over a last by which it is carried, means also moving with the staple guide to jam the upper against the flange of a sole upon said last, thus assisting the pulling action.

3. A lasting attachment for a stapling machine having a staple guide, said lasting attachment comprising spaced apart means upon which the margin of an upper is rested, means located behind the staple guide moving with the staple guide in the stapling operation to press the marginal upper between said spaced apart means producing folds and securing a grip upon the upper to stretch it tightly over a last by which it is carried, means yieldably supporting said spaced apart means permitting movement thereof with and in the direction of movement of said staple guide thereby to exercise said stretching function, and means located in front of said staple guide impinging upon the upper close to a sole upon said last thereby augmenting the stretching function.

4. In a machine for working an upper over a last, means normally situated to receive the margin of an upper when laid thereupon, means which advances upon the marginal upper and presses the marginal upper in respect to said receiving means, thereby to make folds in said marginal upper and take up slack therein, and a mounting for said receiving means so arranged that the receiving means can yield in the direction of pressing movement thereby causing a stretching of the upper upon the last in addition to taking up slack.

5. In a machine for working an upper over a last, a plurality of lasting fingers upon which the margin of an upper is rested, means to advance upon the marginal upper and toward said lasting fingers carrying the marginal upper therewith and producing folds upon said lasting fingers thereby taking up slack, means providing an independent but yieldable mounting for the lasting fingers, permitting a differential motion of the lasting fingers should circumstances so require, and means keeping the lasting fingers under tension tending to resist said differential motion.

6. In a machine of the character described, a plurality of lasting fingers so situated that the margin of an upper can be rested thereupon, means which is normally stationary and in such predetermined normal relationship with the lasting fingers that the marginal upper may be placed in said position but which means is movable to press the marginal upper toward and between said lasting fingers to form folds, and means to adjust the lasting fingers so that the relationship thereof with said pressing means may be altered thereby resulting in the making of more or less pronounced folds.

7. In a machine for working an upper

over a last, a plurality of lasting fingers initially in position to receive the margin of an upper, means normally stationary above the lasting fingers, but movable to press the marginal upper toward and between the lasting fingers to form folds, means to adjust the lasting fingers up and down in respect to the presser means thereby to alter the fullness of the folds when made by the presser means, and means to adjust the lasting fingers longitudinally in respect to the presser means thereby to alter the length of the folds.

8. In a machine for working an upper over a last, a plurality of lasting fingers in position to receive the margin of an upper, means which has an invariable zone of movement to press the marginal upper toward said lasting fingers thereby to form folds, and means providing for adjustments of the lasting fingers in a plurality of directions either singly or in combination and in respect to said presser means while in an initial position thereby producing predeter-

mined variations in the formation of said folds.

9. In a machine for working an upper over a last, a plurality of lasting fingers, means upon which they have common mounting but upon which they are capable of independent pivotal motion, means including springs attached to each lasting finger against the tension of which springs the independent pivotal motion must be exerted, means to press a marginal upper initially superimposed upon said lasting fingers toward and between said lasting fingers thereby causing said pivotal motion which becomes variable should there be any variation in the thickness of the upper upon said lasting fingers, and stationary but adjustable means against which said resilient means acts to maintain the lasting fingers in the initial position in respect to the presser means, the variable function of said lasting fingers being operative regardless of the particular adjustment of said means.

ADAM H. PRENZEL.
